DESIGN FOR A RAIL VEHICLE

Oliver Edward Hyde, New York, N. Y.

Application May 23, 1939, Serial No. 85,165

Term of patent 14 years

To all whom it may concern:

Be it known that I, Oliver Edward Hyde, a citizen of the United States, residing in the city and county of New York, State of New York, have invented a certain new, original, and ornamental Design for a Rail Vehicle, of which the following is a specification, reference being had to the accompanying drawings, forming a part thereof and in which:

Figure 1 is a perspective view of a rail vehicle embodying my new design;

Fig. 2 is a fragmentary side elevational view of the vehicle shown in Figure 1, and

Fig. 3 is a front end elevational view of the vehicle.

Both sides of the design are identical and accordingly only one side is illustrated.

The dominant features of my design are indicated in solid black lines in the drawings.

I claim:

The ornamental design for a rail vehicle, substantially as shown and described.

OLIVER EDWARD HYDE.
